UNITED STATES PATENT OFFICE.

FRANCIS V. PHILLIPS, OF CHICAGO, ILLINOIS, ASSIGNOR TO THE SMITH & PHILLIPS MANUFACTURING COMPANY, OF SAME PLACE.

MACHINE FOR CUTTING WINDOW-STILE POCKETS.

SPECIFICATION forming part of Letters Patent No. 548,454, dated October 22, 1895.

Application filed September 15, 1892. Serial No. 445,959. (No model.)

To all whom it may concern:

Be it known that I, FRANCIS V. PHILLIPS, of Chicago, in the county of Cook and State of Illinois, have invented certain new and useful Improvements in Machines for Cutting Window-Stile Pockets; and I do hereby declare that the following is a full, clear, and exact description thereof, reference being had to the accompanying drawings, and to the letters of reference marked thereon, which form a part of this specification.

This invention relates to machines for cutting pockets in window-strokes, and has for its object to provide a machine by means of which pockets with offset top and bottom ends may be cut at these ends and also at the sides at a single continuous operation.

With this purpose the invention consists in a machine having two side cutters arranged to make the kerfs by which the pocket-piece is laterally detached from the stile, and two end cutters for each end of the pocket, the cutters of each of these pairs of end cutters being offset and arranged to cut from opposite sides of the stile to a plane within the stile. These several cutters may be variously formed, variously mounted, and variously actuated.

In the accompanying drawings, which show one form of such a machine, Figure 1 is a plan view of the machine. Fig. 2 is a side elevation. Fig. 3 is a front elevation. Fig. 4 is a transverse sectional view taken on the line 4-4 of Fig. 2 and looking in the direction of the arrows applied to said line. Fig. 5 is a central longitudinal sectional view of a window-stile, showing one form of pocket produced by the machine shown in the preceding figures.

In said drawings, A represents a frame adapted to support the remaining portions of the machine and provided with inclined end portions A'.

B is the main or driving shaft of the machine, mounted transversely in suitable bearings B' on the main frame A, and provided at one of its ends, which projects beyond the frame for the purpose, with an idle-pulley b, a driving-pulley b', and a fly-wheel b². Near its other end the shaft B is provided with a crank B², to which is connected one end of a

pitman C. The other end of the pitman is pivotally connected with a sleeve C', mounted to slide on a rod or shaft D, which is itself mounted in the main frame in the manner 55 hereinafter described.

E are rods mounted to slide longitudinally in suitable guiding-sleeves e at each end of the machine. These rods are connected at suitable intervals by cross-heads E', each 60 comprising a transverse body or web e', collars e², one at each end, to fit upon the respective rods E, to which they are secured by set-screws e³ or otherwise, and uprights e⁴, one of which extends upward from each collar e². Three of these cross-heads are shown in the present instance, although their number may obviously be varied as required. The uprights e⁴ form two parallel rows, each of which rows carries a saw or cutter F of 70 suitable construction, the upper ends of the uprights being provided with suitable clamping-jaws for holding these saws in vertical planes longitudinally of the machine, with their cutting teeth or projections uppermost 75 and in a horizontal plane. One of the cross-heads E' is connected with the reciprocating sleeve C', and through this connection a simultaneous reciprocatory movement longitudinally of the machine is imparted to the 80 rods E and saws F.

At or near the ends of the rods E, inclined bars E² are attached to these rods, one at each end of the machine. Desirably, one of the rods E extends beyond the other at one end 85 of the machine, while the other projects beyond the first-mentioned one at the other end of the machine to a corresponding extent. The connection between the bars E² and rods E may be of any suitable nature—such, for 90 instance, as that shown, wherein the ends of the rods E are rabbeted to receive each a block e⁵, secured thereon by a clamp-screw e⁶. Each block e⁵ has an aperture through which one end of one of the bars E² passes, and in which 95 it is secured by a set-screw e⁷. On each bar E² is mounted a sleeve E⁸, adapted to slide thereon, these sleeves being secured to the opposite extremities of a longitudinal rod G. This rod G is provided near each end with a 100 transverse rod G', arranged at a right angle thereto and connected therewith by a set-

screw g , or in any other suitable manner. The transverse rods G are mounted to slide in suitable guiding-sleeves g' , so that the longitudinal reciprocation of the rods E will, through the medium of the inclined bars E^2 and sleeves E^3 , produce a simultaneous transverse reciprocation of the rod G .

Upon the rod G are adjustably secured by means of set-screws or otherwise two sleeves h , each of which is provided with suitable clamping-jaws to receive and hold a saw or cutter H . These saws or cutters are of any suitable construction—such, for instance, as that shown—which will adapt them to cut in both directions of their movement, and are arranged to extend upward parallel with each other in an inclined position, which is also parallel with the inclined end portions of the frame A hereinbefore referred to.

Above the rod G is located a similar rod G^2 , parallel therewith and supported and guided by cross-rods G^3 , located one near each end of the rod G , connected therewith by set-screws g^2 , or in any other suitable manner, and adapted to slide in guiding-sleeves g^3 . The rod G has adjustably secured on it two sleeves h' , each adapted to receive and hold a saw or cutter H' , similar to the cutters H and arranged parallel therewith, the cutters H' being, however, located in different planes from the cutters H , and with their cutting-edges directed downward.

The rod G^2 has imparted to it a transverse movement of reciprocation simultaneously with but in the opposite direction from the rod G by means of two levers G^4 , one at each end of the machine, each of said levers being centrally pivoted at g^4 on the frame A or on a projection therefrom. At each of its ends each lever G^4 is provided with a sleeve G^5 , pivoted at g^5 on the lever, and the extended ends of the transverse rods G' and G^3 are bent, respectively, downward and upward to pass loosely through these sleeves, the end of the rod G' passing through the lower one, while the end of the rod G^3 passes through the upper one. By this construction it will be seen that the transverse motion of the lower rod G will be transmitted to an equal extent but in the opposite direction to the upper rod G^2 , and that while in transverse motion the rods G and G^2 may either approach or recede. Suitable means are also provided for feeding the several saws or cutters to their work and withdrawing them from the kerfs. To this end the rod or shaft D is mounted in fixed bearings d at each end of the frame A , so as to be capable of a rocking motion in said bearings, and is provided at one of its ends with a lever D' , by means of which it may be so rocked. Near each end of the rock-shaft D there is secured thereon, by means of a set-screw d' or the like, a cross-bar D^2 , having in each of its ends a slot d^2 . Each of the inclined end portions A' of the frame A is provided with similarly-inclined guiding-ways,

these ways being shown in the present instance as rods or bars I , secured in lugs a projecting from the frame. At each end of the machine there are mounted to slide on these ways two frames J and J' . The frames J are arranged within the frames J' and carry the guiding-sleeves e of the rods E and also the guiding-sleeves g' of the transverse rods G' , which carry the rod G . Each frame J is provided with a pin j , and these pins extend through the slots d^2 in corresponding ends of the cross-bars D^2 . The frames J' surround the frames J and carry the guiding-sleeves g^3 of the transverse rods G^3 , which carry the upper rod G^2 . Each frame J' is provided with a pin j' , and these pins engage the slots d^2 in the ends of the cross-bars D^2 opposite to those engaged by the pins j of the frames J . It will thus be seen that by rocking the shaft D the frames J and J' and the saws carried thereby may be caused to approach and recede from each other in the plane indicated. It is in order to accommodate this motion that the ends of the rods G' and G^3 are passed through and slide within side sleeves pivoted on the levers G^4 , instead of being directly pivoted to said levers. For this same purpose the connection between the sleeve C' and cross-head E' is a sliding one. In this sliding connection a plate c extends upward from the sleeve C' parallel with the ways I , and is slotted, as shown at c' in Fig. 4. From the cross-head E' a similarly-inclined plate C^2 extends downward and is connected with the plate c by means of screw-bolts c^2 , passing through the slot c' and screwing into the plate C^2 .

The material to be operated upon is held stationary, and this may be done in the following manner: The frame A is provided with a horizontal table or rest A^2 , having a central aperture a' , through which the lower cutters work. Lateral guides K rest on this table and hold the work laterally in position, being adjustable toward and from each other and being held after adjustment by means of suitable clamps k . Above the table A^2 there is mounted in the frame A a transverse rock-shaft L , provided with an arm l , by means of which it may be actuated, and upon this rock-shaft there are secured, one at each side of the aperture a' in the table A^2 , two eccentric sectors or cams L' , each provided with a slot l' concentric with the cam-surface and eccentric with relation to the shaft L . On each side of the aperture a' there is located a clamping-plate M , having a bolt m passing through the slot l' and also having a bearing-block m' on which the cam-surface of the sector L' bears. It will be at once seen that by rotating the rock-shaft L in one direction or the other the clamping-plates M may be caused to approach or recede from the table A^2 to clamp the material thereon or release the same, as may be desired. The invention is not, however, limited to this particular form of clamping mech-

anism, as it is obvious that other suitable mechanism for the purpose may be substituted therefor.

In order to render more clear the operation 5 of the machine, there is shown in Fig. 5 a sectional view of a window-stile showing one form of pocket which the machine is adapted to produce, the same forming the subject-matter of an application filed by me October 21, 10 1891, upon which Letters Patent No. 483,968 were issued October 4, 1892, although the 15 form of pocket shown in the present instance is a slight modification of the form shown in the drawings of said application. In the present case the stile N has formed in it a pocket N', having continuous side walls n, parallel with each other and formed by the longitudinal saws F, and indirect end walls, each comprising two offset parallel and inclined portions n' n² and an intermediate portion n³, parallel with the surfaces of the stile. The 20 portions n² are produced by the cutters H and the portions n' by the cutters H', while the intermediate portion n³ is produced by 25 splitting out the pocket-piece. The machine as organized operates to do this work in the following manner: The material to be operated upon is clamped upon the table A² and rotary motion imparted to the shaft B, which, 30 through the pitman C and sleeve C', causes longitudinal reciprocation of the rods E and cutters F carried thereby. At the same time the rods G and G², carrying the cutters H and H', are reciprocated laterally through the connecting mechanism described and provided 35 for that purpose. At the same time the cutters F and H are fed upward through the aperture a' of the table A² into the material from below, while the upper cutters H' are 40 fed downward into the material at an equal rate. This feeding movement is produced by rocking the shaft D by means of the lever D', which, through the medium of the slotted cross-bars D², will move the frames J upward and the frames J' downward simultaneously and to an equal extent. The transverse cutters H H' are desirably so arranged 45 as to each cut through slightly more than one-half of the thickness of the material, so that 50 their cuts overlap to a very slight extent. The cutters F cut entirely through the material. The cutters F are therefore, in the machine as here organized, adjusted with their edges above or more advanced than the edges 55 of the cutters H, so as to complete their cut entirely through the stile when the cutters H shall have advanced only part way through the stile. In other words, the cutters F enter the stock before the cutters H do so, and the 60 cutters H and H' enter the stile at about the same time. When the cutters have finished their cut, the lever D' is used to rock the shaft D in the opposite direction and thus withdraw the cutters from the material, when this latter 65 may be unclamped and withdrawn from the machine. The pocket-piece will be finally detached by splitting the intermediate por-

tions between the cuts of the transverse cutters by a sharp rap of a hammer or other suitable tool, as set forth in my prior application hereinbefore referred to. By adjusting the cutters H and H' the dimensions and form of the pocket may be varied. By bringing the cutters H H nearer to each other than the cutters H' H', so as to cut between the line or cut of these latter, the particular form of pocket shown in my said prior patent may be produced.

Various modifications in the details of construction may be made without departing 80 from the principle of the invention. For instance, the form of the reciprocating frames or carriages which support and impart movement to the cutters may be other than that shown, the rod or bar frame with guiding sleeves which I have devised being a convenient and inexpensive form which is shown merely for purposes of illustration; nor is the inclination of the transverse cutters essential, although in most cases desirable, for it is 85 manifest that these cutters may be vertical, and the correspondingly-inclined other parts of the machine will then be also vertical. Moreover, the specific forms of actuating and connecting mechanism may obviously be varied, the same not being an essential part of 90 the invention, which is not limited to the particular details shown and described.

What I claim is—

1. A machine for cutting window-stile pockets or the like, comprising two cutters for cutting the sides of the pocket, and two oppositely directed pairs of cutters arranged transversely to those first mentioned and operating on the material from opposite sides to a plane 105 intermediate to the surfaces of the board, for cutting the ends of the pocket.

2. A machine for cutting window-stile pockets or the like, comprising means for holding stationary the material to be operated upon, two cutters for cutting the sides of the pocket, two oppositely directed pairs of cutters arranged transversely to those first mentioned and operating on the material from opposite sides to a plane intermediate to the surfaces 110 of the board, for cutting the ends of the pocket, and means for simultaneously advancing said cutters into the material and withdrawing them therefrom, substantially as described.

3. A machine for cutting window-stile pockets or the like, comprising two cutters for cutting the sides of the pocket, and two oppositely directed pairs of cutters arranged transversely to those first mentioned, the cutters of each pair being offset or in different planes 125 and arranged to operate on the material of the stile from opposite sides thereof to a plane intermediate to the surfaces of the stile, for cutting the ends of the pocket.

4. A machine for cutting window-stile pockets or the like, comprising means for holding stationary the material to be operated upon, two reciprocating cutters for cutting the sides of the pocket, two oppositely directed pairs

of reciprocating cutters arranged transversely to those first mentioned in parallel inclined planes and operating upon the material from opposite sides to a plane intermediate to the surfaces of the board, for cutting the ends of the pocket, and means for simultaneously advancing said cutters into the material and withdrawing them therefrom, substantially as described.

10. In a machine for cutting window-stile pockets or the like, the combination, with a supporting frame, of a longitudinally reciprocating carriage having two parallel cutters arranged with their cutting edges upward, a transversely reciprocating carriage connected with and actuated by the first mentioned carriage and having two parallel cutters arranged between and at right angles with the longitudinal cutters, with their cutting edge upward, and a second transversely reciprocating carriage connected with and actuated by said first mentioned transversely reciprocating carriage, and provided with two cutters parallel with those of said last mentioned carriage, and having their cutting edge downward, substantially as described.

15. In a machine for cutting window-stile pockets, the combination, with a supporting frame, of a longitudinally reciprocating cutter carriage provided with inclined bars, a transversely reciprocating cutter carriage engaged with said bars, a second transversely reciprocating cutter carriage, and a centrally pivoted lever having its ends respectively connected with the two latter carriages, substantially as described.

20. In a machine for cutting window-stile pockets, the combination, with a supporting frame provided with guiding ways at its ends, of two frames mounted on said ways at each end of the frame, a longitudinally reciprocating and a laterally reciprocating cutter carriage mounted in one pair of said frames, a laterally reciprocating cutter carriage mounted 25 in the other pair of frames, and means for simultaneously moving said pairs of frames in opposite directions, substantially as described.

25. In a machine for cutting window stile pockets, the combination, with end frames movable in opposite directions, of transversely reciprocating cutter carriages respectively mounted on said frames, and a centrally pivoted lever having pivoted and sliding connection with said cutter carriages.

30. In a machine for cutting window-stile pockets, the combination, with a main frame having a fixed work rest provided with an opening, of two longitudinal side cutters and two transversely arranged end cutters, both sets of said cutters being arranged on the same side of the stile as the work rest and adapted to be advanced through the opening in the work rest into the window stile, and a second set of similar end cutters arranged on the opposite side of the stile and adapted to be advanced toward the stile simultaneously with the cutters before mentioned.

35. In a machine for cutting pockets in window stiles, a pair of reciprocating side cutters, two end cutters arranged on the same side of the work as the side cutters and having their cutting edges less advanced than said side cutters, and two other end cutters arranged on the opposite side of the work, whereby, upon the advance of the cutters from opposite sides of the stile to be cut, the side cutters will work through the stile while the end cutters are working to a plane intermediate to the opposite surfaces of the stile.

In testimony that I claim the foregoing as my invention I affix my signature in presence of two witnesses.

FRANCIS V. PHILLIPS.
